DESIGN FOR AN OUTDOOR SIGNBOARD

Roger W. Olmsted, San Francisco, Calif.

Application February 8, 1945, Serial No. 117,831

Term of patent 14 years

(Cl. D1—12)

To all whom it may concern:

Be it known that I, Roger W. Olmsted, a citizen of the United States and a resident of the city and county of San Francisco, State of California, have invented a new, original, and ornamental Design for an Outdoor Signboard, of which the following is a specification, reference being had to the accompanying drawing, forming a part thereof.

Fig. 1 is a perspective view of an outdoor signboard showing my new design.

Fig. 2 is an end view.

Fig. 3 is a top plan view thereof.

The essential and characteristic features of the design are shown in full lines in the drawing.

I claim:

The ornamental design for an outdoor signboard, substantially as shown and described.

ROGER W. OLMSTED.
